United States Patent Office.

JAMES L. JUDGE, OF MILWAUKEE, WISCONSIN.

Letters Patent No. 90,176, dated May 18, 1869.

IMPROVEMENT IN STEAM-HEATERS.

The Schedule referred to in these Letters Patent and making part of the same.

To all whom it may concern:

Be it known that I, JAMES L. JUDGE, of the city and county of Milwaukee, and State of Wisconsin, have invented a new and useful Improvement in Steam-Heaters; and I do hereby declare that the following is a full, clear, and exact description thereof, which will enable those skilled in the art to make and use the same, reference being had to the accompanying drawing, forming part of this specification, in which—

Figure 1 is a vertical perspective view;

Figure 2, a vertical sectional view;

Figure 3, a cross-sectional view in the line *z z*, fig. 2; and

Figure 4, a view of the base of my invention.

Similar letters of reference in each of the figures indicate corresponding parts.

The nature of my invention is to produce a steam-heater which will be economical and easy to take care of.

A is the outside shell.

B, the base.

C, the fire-door.

D, door in the top of the smoke-stack.

E, a central water-circulator.

F, arms by which circulator E is connected to the corrugations in the fire-box.

G, fire-draught flues, which pass down into the base of the fire-box, from the top of the box.

H, flues which take the draught from the flues G, and conduct it to the smoke-stack, up through the water and steam.

I, steam-chamber above the fire-box.

K, corrugations in the fire-box.

L, door through which to clear the ashes from the base.

M, a door in the back side of the box, which, when opened, lets the cold air into the tubes, and cools the water when it gets too hot.

N, another door for cleaning out ashes.

O, the ash-pan.

P, the smoke-stack.

Operation.

Fill the steamer with water about a foot above the fire-box door. This will be done through a pipe which passes into the bottom of the steamer, which is not shown in the drawings; nor, either, is the passage for the escape of steam shown, as that is not necessary. Then build a fire in the fire-box. The smoke will pass down through flues G, and up through flues H, and out through the smoke-stack. (There is a larger number of both flues G and H in a heater in practical operation than those in the drawings.) The water will be heated, steam will be generated rapidly and pass off, and warm the house.

What I claim as my invention, and desire to secure by Letters Patent, is—

1. The steam-heater, constructed with shell A, circulator E and F, flues G and H, and corrugations K, all arranged substantially as described.

2. Base B, with doors L, M, N, and O, and holes to correspond with the flues G and H, arranged substantially as described.

3. Circulator E and F, flues G and H, corrugations K, steam-chamber I, with shell A, constructed and arranged substantially as described.

JAMES L. JUDGE.
